His, Attorney

UNITED STATES PATENT OFFICE.

JOSHUA W. HARRIS, OF AVIS, VIRGINIA.

TRANSPLANTER.

SPECIFICATION forming part of Letters Patent No. 340,211, dated April 20, 1886.

Application filed July 22, 1885. Serial No. 172,260. (No model.)

To all whom it may concern:

Be it known that I, JOSHUA W. HARRIS, a citizen of the United States, residing at Avis, in the county of Augusta and State of Virginia, have invented certain new and useful Improvements in Transplanters, of which the following is a specification, reference being had therein to the accompanying drawings.

This invention has relation to improvements in transplanters; and it consists in the construction and novel arrangement of parts, as will be hereinafter described, and particularly pointed out in the claims.

In the accompanying drawings, Figure 1 is a perspective view of my invention. Fig. 2 is a vertical section thereof. Fig. 3 is a view of a link or a connecting-rod to be sometimes used.

Referring to the drawings, the letter A represents the casing of my improved transplanting machine, having at its top portion a frame, A', provided with a cross-piece, B, cut away at its middle portion to form a hand-hold, a, as shown in Fig. 1. At each end of this cross-piece, and pivoted in suitable bearings thereon, are the arms b b', which are hinged together at their inner ends, as shown, and provided with elongated slots b², which allow an easy backward and forward movement of said arms when the machine is operated. The cross-piece B is also provided with a spring, c, which abuts against the under side of one or both of the arms, whereby said arms are thrown upward when released. The spring may be made of any well-known construction.

Pivoted to the bottom of the casing A, and on each side thereof, are the shovels or planters D D', provided at their sides with extensions d d', having hinged thereto the lower ends of the levers f f', the upper ends of these levers being hinged to the ends of the arms b b'.

The letters C C' denote the coverers or hoes, hinged to the sides of the casing in any suitable manner, and having arms c c', to which are pivoted the lower ends of the arms g g', the upper ends of these arms being pivoted to the ends of a handle, M, said handle being hinged to the sides of the casing, as shown in Fig. 1. This handle is provided with springs h h', secured on each side of the casing.

On the inside of the casing I secure, in any

suitable manner, a pipe or feeder, L, having at its top a flaring mouth-piece, l. This mouth-piece is removable to the other side of the casing, and can be fed from that side by a second person, thereby relieving the operator from feeding the machine, if so desired.

The letter T indicates a plunger-rod secured to one side of the casing A, to hold the machine in contact with the ground, to prevent lateral movement of said machine when the plant is to be set. The rod is provided with a ring, t, encircling its body portion, and having a set-screw, t', whereby said ring can be adjusted vertically on said plunger-rod, to regulate or gage the desired depth the planters D D' are to enter the ground to make an opening therein for the plants.

I wish it to be understood that in planting in soft soil I can dispense with the handle M and arms g g', and attach a link or connecting-rod, O, to the ends of the arms c c' and to the extensions d d' of the shovels. I further desire it to be understood that I do not confine myself to the precise construction shown in my invention, as I may deviate from the same without departing from the true spirit and scope thereof.

The operation of my machine is as follows: The arms b b' and hand-hold a are grasped by the right hand of the operator. Said arms are then pressed downward, which causes the shovels or planters D D' to spread apart, as shown in Fig. 2. The handle M is then brought into action by means of the left hand or knee of the operator, to close the hoes or coverers C C' and press the soil toward the plant in the pipe. Said handle is then released, which opens the coverers and leaves the plant deposited in the ground. The arms b b' retract to their original position by means of a spring, c, which closes the planters.

Having described my invention, what I claim is—

1. In a transplanter, the combination, with the casing having at its top portion a cross-piece having pivoted in suitable bearings arms b b', pivoted together at their inner ends and provided with elongated slots, of a spring, c, connected to said cross-piece and bearing under said arm or arms, as shown and described.

2. In a transplanter, the combination, with the casing, cross-piece B, spring c, pivoted arms b b', shovels D D', hoes or coverers C C', and the handle M, of the levers f f' and arms g g', said levers connected to the ends of the arms b b' and to the shovels, the arms g g' pivoted to the handle and grippers, and the feed-pipe L, having the reversible mouth-piece l, as shown and described.
- 10 3. The transplanter herein described, consisting of the casing A, cross-piece B, having spring c, the arms b b', pivoted to the cross-piece and provided with elongated slots b², the feed-pipe L, having the reversible mouth-piece l, the shovels D D', pivoted to the

bottom of the casing, the hoes or coverers C C', hinged to the sides of the casing, the levers f f', pivoted to the ends of the arms b b' and to the shovels, and the arms g g', connected to the handle M and to the coverers, as shown 20 and described.

4. The combination, with a transplanter, of the plunger-rod having a gage-ring and set-screw, as and for the purposes set forth.

In testimony whereof I affix my signature in 25 presence of two witnesses.

JOSHUA W. HARRIS.
